[57] CLAIM

The ornamental design for a module for a multipurpose utility station for use at e.g. a petrol station, providing e.g. supplies of air, oil, screen washer fluid, coolant as well as washing facilities, as shown and described.

DESCRIPTION

FIG. 1 is a front perspective view of the module for a multipurpose utility station for use at e.g. a petrol station, providing e.g. supplies of air, oil, screen washer fluid, coolant as well as washing facilities embodying my new design;

FIG. 2 is a front perspective view of the module for a multipurpose utility station for use at e.g. a petrol station, providing e.g. supplies of air, oil, screen washer fluid, coolant as well as washing facilities embodying my new design; and,

FIG. 3 is a rear perspective view of the module for a multipurpose utility station for use at e.g. a petrol station, providing e.g. supplies of air, oil, screen washer fluid coolant as well as washing facilities embodying my new design.
